INVENTOR:
WILLIAM BOSS.
BY Whitley and Ruckman
ATTORNEYS

UNITED STATES PATENT OFFICE.

WILLIAM BOSS, OF ST. PAUL, MINNESOTA.

HUMIDIFIER.

Application filed April 7, 1922. Serial No. 550,543.

To all whom it may concern:

Be it known that I, WILLIAM Boss, a citizen of the United States, residing at St. Paul, in the county of Ramsey and State of Minnesota, have invented certain new and useful Improvements in Humidifiers, of which the following is a specification.

My invention relates to humidifiers for use particularly in connection with steam radiators or hot water radiators, and an object is to provide efficient means for keeping the air in the rooms containing the radiators in moist condition. Particular objects are to provide a humidifier which may be conveniently and economically manufactured, which may be readily installed in place upon a radiator, which will insure rapid evaporation of water, and which will act to collect dust which is carried upwardly by the current of hot air rising from the radiator.

The full objects and advantages of my invention will appear in connection with the detailed description, and the novel features embodied in my inventive idea will be particularly pointed out in the claims.

In the accompanying drawings which illustrate one form in which my invention may be embodied, Fig. 1 is a front elevational view of the humidifier. Fig. 2 is a view of the humidifier in vertical longitudinal section showing it in place upon the top of a radiator. Fig. 3 is an end elevational view. Fig. 4 is a view of the humidifier in vertical transverse section showing it in place on the top of a radiator. Fig. 5 is a view in horizontal section on the line 5—5 of Fig. 4. Fig. 6 is a fragmentary sectional view of the fabric which I employ. Fig. 7 is a fragmentary plan view of the fabric.

As shown in the drawings, I provide a casing 10, the front portion of which is provided with a bottom 12 to constitute a water receptacle. The rear wall of this receptacle is constituted by a partition 14 which is spaced forwardly from the rear wall of the casing so as to provide a vertical passage-way 16 for the hot air rising from the radiator. A plurality of horizontal rodlike supports 18 extend above the water receptacle from front to rear, these supports having end portions 20 which are bent downwardly at right angles for securing the supports 18, these end portions being preferably soldered to the front and rear walls of the

casing 10. The fabric 22 having a width 55 substantially the same as that of the water receptacle is folded back and forth over the supports 18 so as to have portions extending down to the bottom of the water receptacle and other portions extending horizontally above the receptacle, these lower portions and upper portions being connected by vertical portions of the fabric as will be apparent from Fig. 2. I provide a cover 24 for the casing 10, this cover having a peripheral depending flange portion, the rear of which when the cover is in place forms an upward continuation of the rear wall of the casing whereby a deflector is formed. The front portion and the forward side portions 70 of the peripheral flange are provided with perforations or slots 26 as shown in Figs. 1 and 3 for escape of the moistened air. The cover may be securely held in place by horizontal supports 28, the end portions of which 75 are bent downwardly at right angles and soldered to the casing at the two ends of the latter. The front portion of the water receptacle is provided with a shield 30 within which is a float 32 to which is secured a vertical rod 34, the upper end of which is bent forwardly so as to extend through a slit 36 in the cover flange and is provided with a head 38 upon observing which the amount 80 of water in the receptacle is indicated. 85

The operation and advantages of my invention will now be apparent. The humidifier is placed on top of the radiator R so that the rear wall of the casing in connection with the rear flange of the cover constitutes 90 a deflector which in use will engage the wall of the room or the window ledge L as shown in Fig. 4 and cause the hot air rising from the radiator to pass up through the passage-way 16 and then forwardly through the device from which it escapes through the slots 26. The fabric which I employ is preferably one having a pronounced nap as shown in Figs. 6 and 7. Moisture is drawn up into the fabric by capillarity and is quickly picked 100 up by the forwardly passing current of air impinging upon the projecting nap. At the same time particles of dust carried by the air are retained. On account of the solid top portion of the cover, the moistened air 105 is forced to pass out into the room through the slots 26 and the cover may be utilized as a support for various articles. The water

receptacle may be filled through any one of the perforations 26 without removal of the cover.

I claim:

- 5 1. A humidifier comprising a casing adapted to rest upon the top of a radiator, a water receptacle constituted by the forward portion of said casing, the rear wall of said casing being substantially parallel to 10 and of the same height as the rear wall of said water receptacle whereby a vertical passageway is formed for heated air from the radiator, a plurality of rods having horizontal portions extending above said water receptacle between the front and rear thereof for supporting a fabric with portions thereof extending down into said water receptacle and 15 having downwardly bent ends secured to said casing, a cover for said casing for causing the heated air passing through said passageway to impinge upon said fabric, said cover having peripheral depending front, 20 rear and end flanged portions, the rear flanged portion forming an upward continuation of the rear wall of said casing, and the front flanged portion and end flanged portions being provided with perforations 25 for the escape of moistened air, and two rods at the ends of said casing having horizontal portions located above said first mentioned horizontal portions and having downwardly bent ends secured to said casing whereby a support for said cover is formed.
2. A humidifier comprising a casing adapted to rest upon the top of a radiator, a water receptacle constituted by the forward

portion of said casing, the rear wall of said casing being substantially parallel to and of the same height as the rear wall of said water receptacle whereby a vertical passageway is formed for heated air from the radiator, a plurality of rods having horizontal portions extending above said water receptacle between the front and rear thereof for supporting a fabric with portions thereof extending down into said water receptacle and 35 having downwardly bent ends secured to said casing, a cover for said casing for causing the heated air passing through said passageway to impinge upon said fabric, said cover having peripheral depending front, 40 rear and end flanged portions, the rear flanged portion forming an upward continuation of the rear wall of said casing, and the front flanged portion and end flanged portions being provided with perforations 45 for the escape of moistened air, and two rods at the ends of said casing having horizontal portions located above said first mentioned horizontal portions and having downwardly bent ends secured to said casing whereby a support for said cover is formed.

In testimony whereof I hereunto affix my signature.

WILLIAM BOSS.
